KEY ARRANGEMENT

Ernst Bähr, Berlin-Charlottenburg, Germany,
assignor to Siemens and Halske, Aktiengesell-
schaft, Berlin-Siemensstadt, Germany, a cor-
poration of Germany

Application May 13, 1938, Serial No. 207,686
In Germany May 13, 1937

4 Claims. (Cl. 178—66)

This application concerns a new and improved signalling system. In describing the invention reference will be made to the attached drawings wherein:

5 Figures 1 and 3 to 8 inclusive illustrate various modifications of my novel and improved means for relaying and forming wave energy to impose thereon signal characteristics. Each of the circuits illustrated includes two or more 10 pairs of rectifiers or other non-linear devices connected in balanced or symmetrical circuits with means for impressing the wave energy to be modulated on the circuit and formed wave energy from the circuit. In Figure 1 the balanced keyer 15 or modulator has two non-linear devices in series, and a second pair of non-linear devices are connected in shunt to the balanced circuit. Figure 2 is a graph representing the operation of my new and improved keying scheme. In Figure 3 the series non-linear devices are replaced by groups of such devices while in Figure 4 the two shunt devices are replaced by several such devices. The circuits of Figures 5 and 6 are modifications of Figure 1 and in Figures 5 and 6 20 the shunt non-linear devices are connected differently than in Figure 1. In Figure 7 a bridge circuit comprising arms including non-linear devices of Figure 1 while in Figure 8 a bridge circuit similar to the one in Figure 7 replaces the series non-linear devices. Modified forms of coupling transformers are used in Figures 7 25 and 8.

A network for keying alternating current comprises a transformer 22 having its primary winding 14 connected to a source of wave energy 13 to be keyed and its secondary winding 19 coupled to an output line 7 by other means such as a transformer 31. The line 7 may be coupled 30 to any load represented at 10. A resistance 15 may be included in the supply circuit if necessary to keep the current substantially constant. Points on the windings 19 and 31 are connected with any source of keying potentials or current 35 such as, for example, comprised by source 5, keys 6 and 9. Two pairs of detectors (non-linear devices) 1, 2 and 3, 4 in series are inserted in the series branches and parallel branch respectively of the balanced circuit. The biasing potential of said detectors can be varied in its direction by means of a key 6 connected to the source of direct current or alternating current 5. The damping of the network between the poles a, b, c, and d varies within such wide limits, as for 40 instance between a damping when the circuit 45

is keyed to pass current of $b_D \leq 0.2$ Neper and the damping when the circuit is keyed to block current from passing $b_S \geq 4$ Neper, that the four-pole permits passage of alternating current from the source 13 at a low resistance of the detectors 1 and 2 in the series branches and high resistance of the detectors 3, 4 in the parallel branch but blocks the alternating current when the resistance of the series detectors 1, 2 is high and that of the parallel detectors 3, 4 is low.

This known arrangement has the disadvantage that when the control current from source 5 is shut off, currents appear in the receiving relay 10 connected to the outgoing line 7, the value of said currents lying approximately in the center between the currents appearing at passage I_D and at blocking I_S of the keying arrangement as illustrated in Figure 2. When 10 includes a receiving relay, current will be supplied thereto of a value of the order required to operate the receiver. Therefore, the position of the armature of the receiving relay is no longer unequivocally established. In case of fluctuations of the residual damping of the line 7 the armature of the receiving relay 10 will thus move to and fro and give the wrong impression at the receiving station of the character of telegraphic signals on the line 7.

The shutting off of the current source 5 is ordinarily done in the telegraph offices if longer intervals between the transmitting of messages 30 occur such as for instance at night.

My invention relates to an arrangement by which the aforementioned disadvantage is eliminated and whereby in the condition of substantially zero control potential, the damping (b_0 Neper) of the key arrangement deviates only to such a slight degree from the damping at passage (b_D) or damping at blocking (b_S) that in the presence of this slight variation in the damping of the line, the receiving relay remains in an 40 unequivocal position.

This is achieved in accordance with the invention making the resistances of the series branch detectors 1 and 2 and parallel branch detectors 3 and 4 greatly different from each other. It is advisable so to choose the value of the null-damping that b_0 is outside the range 3 Neper $\leq b_0 \leq 3b_D$. At these values of b_0 even in the presence of variations of the level such as appear ordinarily during telegraphic transmissions, the receiving relay remains attracted or released at the null value of the control potential, without the relay being permitted to fluctuate between these two values.

Various ways are possible in obtaining the difference between the resistance values of the rectifiers inserted in the series branch and parallel branch, more especially of the dry-contact rectifiers. Thus, in the series branch several detectors in parallel may replace the single detectors 1 and 2 as shown in Figure 3 or in the parallel branch several detectors may be placed in series as shown in Figure 4 or vice versa, or there is employed a combination of these two arrangements. The circuits of Figures 3 and 4 are otherwise similar to these of Figure 1 with keying means connected at points 40.

It will be especially suitable to connect the detectors in the series branch and parallel branch to the input transformer of the key circuit across different reduction ratios. The reduction ratio thereby has the effect that as regards the total damping of the network the resistances in the series branch and parallel branch vary in accordance with the square of the ratio between the windings. Therefore, the b_0 value comes very close either to the damping value at passage or to the damping value at blocking.

If the control potentials are derived in the two directions in the ordinary manner from the same direct current source, it will, furthermore, be advisable by providing resistances in series or parallel to the current source and tapped at different places, to apply the control potential at such a value to the different detector combinations in the series branch and parallel branch, that for each individual detector the control potential has a favorable value, this value depending on the characteristic of the detector. Such arrangements have been shown in Figure 5. In Figure 5 resistances 23, 24 and 25 are connected between the adjacent terminals of the non-linear devices 3 and 4 and the point at which the keying circuit is connected to the primary 31, which in this case is split into two portions separated by a blocking condenser. The detectors 3 and 4 shunt a portion only of secondary winding 48.

In place of the series or parallel connection of detectors in the series branch or parallel branch there may also be employed a bridge circuit of the type of the so-called Graetz circuit in which the control potential is in one diagonal, and the voltage to be controlled in the other diagonal. In Figure 7 the parallel detectors 3 and 4 have been replaced by a bridge arrangement comprising detectors 27, 28, 29 and 30. In Figure 8 the series detectors 1 and 2 have been replaced by the said bridge circuit which is in one side only of the line. In both of these modifications a transformer having two windings 19' and 19'' with different transformer ratios are used. This arrangement has the advantage that though a multiplicity of detectors is present, these detectors have as regards carrier frequency the effect of a single detector.

With the arrangement according to the invention, on complete shutting off of the control voltage sources telegraphic signals heretofore carried by current variations, are no longer simulated. The arrangement according to the invention can moreover also be readily used for single current operation, especially when the single transmission key is connected to the center of the control voltage source. By resorting to particular circuits alternating current telegraphy has been operated heretofore with single current polarized transmission relays. These known arrangements

had the following disadvantages. It was necessary to provide a compensation winding and a special compensation current whose value had to be accurately adjusted. Different response periods were encountered at turning of the relay armature out of the null position, furthermore the relay kicked back, i. e., the armature was lifted again although contact was already made. The switching period was greater and varied within wide limits. At a high and brief load as well as at a unilateral load of longer duration, the mechanical and magnetic neutral position of the relay disappeared, so that the relay was after a certain time no longer neutral and finally the telegraphic speed was limited in the case of contact relays owing to the inertia of the mass. These drawbacks resulted in detrimental distortions of the telegraphic signals.

The above disadvantages are overcome by the transmission key circuit according to this invention. Additional distortions are eliminated and furthermore the transmitter key circuit can also be operated with single current in the same advantageous manner and without modifications being necessary. More especially, the telegraphic speed is not limited in the key circuit according to the invention since this arrangement operates without inertia.

The operation of my invention will now be explained in greater detail with reference to several examples of construction. In Figure 1 two detectors 1, 2 and 3, 4 are placed respectively in the series branch and in the parallel branch. In accordance with the position of the transmitter key 6 either the detectors in the series branch or those in the parallel branch permit passage of current. Therefore, currents I_D and I_S appear at the receiving relay whereby the current (I_D) in the direction of passage is much greater than that (I_S) in the direction of blocking. The response amperage and release amperage of the receiving relay are approximately the half amperage of I_D , as shown by the straight line 11 in Figure 2. In Figure 2 the abscissa represents the time (t) and the duration of a pause between two telegraphic signals ($t_2 - t_1$) is shown below the abscissa.

Now, if for instance during the night the control voltage source 5 is shut off at the office in that the switch 9 for instance is opened, the detectors 1 and 2 in the series branch and detectors 3 and 4 in the parallel branch have the same resistance. Therefore, the current in the network will pass with one half across the parallel circuit and with the other half across the series circuit. Since the total current, and this is also assumed for all following examples, is to be maintained practically constant in that the resistor 15 placed in series to the alternating current source 13 and primary winding 14 of the input transformer is chosen about 100 times larger than the resistance of the network inclusive the load of the outgoing line 7 of the order of about 100 ohm, the current I_s of the generator flowing in the circuit 13, 14, 15 is practically independent of the load of the transformer 22 and therefore, as above stated, in a circuit according to Figure 1 the current appearing at the receiver is at interruption through the switch 9 one half of the current I_D in the direction of passage.

This amperage is shown in Figure 2 by the straight line 16 which in the present case conforms to the response amperage and release amperage of the receiving relay. Figure 2 readily indicates that in case of variations in the damp-

ing of the line and variations of the current I_6 caused thereby, the current I_6 easily exceeds or lags behind the response limit and release limit 11 of the relay in the one or the other direction, so that the receiving relay begins to vibrate and simulates reception of telegraphic signals. The invention provides means whereby the amperage in the receiving relay can be displaced at zero control potential towards higher or lower values in such a manner that it lies sufficiently far apart from the response limit and release limit of the receiving relay such as for instance in the position 17 or 18 .

Figure 3 shows an example of an arrangement according to the invention. Herein, the detectors 1 and 2 in the series branch are replaced by four detectors of the same size as that of the detectors 3 and 4 and placed in parallel. Consequently, at zero control potential only $\frac{1}{2}$ of the current flows in the parallel branch, but $\frac{1}{2}$ pass through the series branch so that the receiving relay 10 receives a current that is 80% of the current I_D and this current being far away from the release limit of the relay.

In a similar manner Figure 4 shows in the parallel branch several detectors for instance three detectors placed in series. Therefore, if the control potential is zero, the current $I_0 = \frac{1}{4}$ of I_D as indicated by the straight line 18 in Figure 2. This amperage is sufficiently far below the response limit of the receiving relay so that at the current I_0 the position of the armature of the receiving relay is the same as at the blocking current I_S .

In order to enhance the actions attained with the arrangements according to Figures 3 and 4 also both circuits can be combined and detectors in parallel can be employed in the series branch and detectors in series can be inserted in the parallel branch. Vice versa, detectors placed in series may be inserted in the series branch and detectors placed in parallel may be inserted in the parallel branch.

In order to operate with a smaller number of non-linear means than that required for the series connection and parallel connection of several detectors, it is advisable to use an arrangement according to Figure 5, in which the parallel and series detectors are coupled at a different ratio with the primary winding of the transformer 22 . The particular advantage of different reduction ratios resides in that the resistance of the detectors varies as regards current distribution with the square of the transmission ratio. The arrangement according to Figure 5 corresponds as regards action approximately to those of Figures 3 or 4 while the arrangement of Figure 6 reveals the contrary conditions of the damping. In the arrangement of Figure 5, resistors 23 , 24 , 25 are inserted in the control circuit. They are so dimensioned that all detectors have linearity while the control current which renders the detectors of the one direction previous increases the negative blocking potential for the other detector pair due to the voltage drop of the said control current at the resistors 25 and 23 and 24 . The condenser

26 serves for bridging the resistors 23 and 24 as regards alternating current.

Figure 7 shows a transmitter keying circuit in which the detectors in the parallel branch designated by 3 , 4 are replaced by four detectors 27 , 28 , 29 , 30 in bridge connection. The resistance of the combination consisting of these four detectors is, as regards the carrier frequency, equal to the resistance of a single detector, this being true for the controlling current as well as for the controlled current applied to and derived from the diagonal points. The shunt action of this parallel detector is still further increased in the arrangement of Figure 7 in that the current to be controlled is passed to the primary side of the input transformer across a special winding $19'$ whose reduction ratio is 1:10, while the series detectors are placed at a third winding $19''$ of the input transformer whose transmission ratio is 1:2. The transmission ratio of the output transformer 31 is 2:1. The resistors 32 , 33 , 34 , 35 and 36 are again so dimensioned that the direct control potential has the same value at each individual detector.

Finally, Figure 8 shows an arrangement in which the Graetz or bridge connection is in the series circuit and not in the parallel circuit.

I claim:

1. In a keying system, a wave energy source, a utilization circuit including a device responsive to wave energy which varies about a selected amplitude, rectifier means in a series circuit coupling said source of wave energy to said utilization circuit, rectifier means effectively in shunt to said series circuit, a control circuit including a variable source of potential and means for varying said potential connected in shunt to said series and shunt rectifier means to bias the same to pass wave energy to said utilization circuit of an amplitude which varies as the bias on the respective rectifier means varies and means for preventing wave energy from said source of an amplitude of the order of said selected amplitude from being impressed on said utilization circuit in the non-keying condition of said control circuit comprising means connected with one of said rectifier means to change the resistance of the circuit including the said rectifier means to thereby alter the amplitude of the wave energy passed by said one rectifier means and consequently the wave amplitude of the wave energy passed from said source to said utilization circuit so that it differs from said selected amplitude by a substantial amount.

2. A system as recited in claim 1 wherein said last named means comprises additional rectifiers in shunt with one of said rectifier means.

3. A system as recited in claim 1 wherein said last named means comprises additional rectifier means inserted in series with said effective shunt circuit to raise its impedance.

4. A system as recited in claim 1 wherein said last named means comprises additional rectifier means in shunt to the rectifier means in said series circuit to lower its impedance.

ERNST BÄHR.
